UNITED STATES PATENT OFFICE.

DANIEL MILLS, OF PHILADELPHIA, PENNSYLVANIA.

FRICITION-CLUTCH.

SPECIFICATION forming part of Letters Patent No. 286,214, dated October 9, 1883.

Application filed March 5, 1883. (No model.)

To all whom it may concern:

Be it known that I, DANIEL MILLS, a citizen of the United States, and a resident of Philadelphia, Pennsylvania, have invented an improvement in Friction-Clutches, of which the following is a specification.

My invention consists of an improvement in the construction of that class of friction-clutches in which a split ring and rimmed or flanged wheel are combined with a pivoted lever for expanding the ring against the rim of the wheel, as more fully described hereinafter, the device being more particularly applicable as a means of imparting an intermittent rotary motion to a shaft, as in the feed-motion of a sewing-machine, for instance.

In the accompanying drawings, Figure 1 is a perspective view of the several parts of the device detached from each other. Fig. 2 is a side view. Fig. 3 is a similar side view with the operating-lever in section, but indicated by dotted lines; and Fig. 4 is a view of a modification.

A is the shaft to which an intermittent rotary motion is to be imparted through the medium of the devices hereinafter described, and on this shaft is mounted a wheel or disk, B, having an annular rim or flange, b. Within this rim is fitted a split ring, D, in frictional contact with the rim. A projection or arm, d, near one end of this split ring, is provided with a pivot-pin, e, on which is mounted the curved operating-lever E, with a projecting outer end, e', to be acted on for imparting the necessary vibrating motion to the said lever. The opposite end of the lever is provided with a lug or projection, F, which is adapted to occupy the space between the ends of the split ring, with a slight play between them. On imparting motion in the direction of the arrow, Fig. 2, to the end of the lever E the ring D will immediately be caused to expand and bind firmly against the inner face of the rim of the wheel B, and cause the latter to turn

to an extent varying with the extent of motion of the lever E. On the return movement of the latter the ring will be released and will slip within the rim of the wheel, back motion of the wheel being prevented by a suitable friction device, preferably applied to the periphery of the wheel. If, however, the split ring D does not in the first instance bear on the interior of the rim b with a certain amount of friction, the movement of the lever E will simply cause the split ring to slip around within the wheel without expanding it sufficiently to bind against the rim. In order to insure, therefore, at all times a proper amount of friction between the split ring and rim, I introduce between the lug F and the end of the ring carrying the arm d a spring, f, which tends to keep the split ring always in sufficient frictional contact with the rim to insure the binding of the ring against the rim when the lever E is moved in the direction of the arrow, but which will allow the ring to slip within the rim on the return movement of the lever.

In the device shown in Figs. 1, 2, and 3 the spring is of a helical form, and adapted to a pocket in the lug F, while in the device shown in Fig. 4 the spring is of a somewhat modified form, which will be readily understood without description.

I claim as my invention—

The combination of a flanged wheel or disk with a split ring in frictional contact with the rim of the wheel, an expanding-lever, and a spring, f, interposed between the said lever and one end of the split ring, substantially as shown and for the purpose set forth.

In testimony whereof I have signed my name to this specification in the presence of two subscribing witnesses.

DANL. MILLS.
